CLAIM

The ornamental design for a switch, as shown and described.

DESCRIPTION

FIG. 1 is a front, right, top perspective view of a toggle switch showing the new design;
FIG. 2 is a front view thereof;

FIG. 3 is a rear view thereof;
FIG. 4 is a left side view thereof;
FIG. 5 is a right side view thereof;
FIG. 6 is a top view thereof; and,
FIG. 7 is a bottom view thereof.

The dashed lines in the drawings represent portions of the design that are not claimed.
